UNITED STATES PATENT OFFICE.

FORREST S. BLANCHARD, OF STONEHAM, MASSACHUSETTS, ASSIGNOR TO IDEAL CAN COMPANY, OF EVERETT, MASSACHUSETTS, A CORPORATION OF MASSACHUSETTS.

SAFETY CAN.

Application filed July 13, 1927. Serial No. 205,495.

This invention relates to safety cans used to store and dispense a limited quantity of gasoline, or other volatile liquid, such cans being used, for example, to carry, on a motor vehicle, a spare supply of gasoline and dispense the same into the storage tank, or the vacuum tank of the vehicle, the can being provided with means for automatically closing the opening through which it is charged 5 and through which liquid is discharged. 10

The object of the invention is to provide a safety can of improved construction, whereby the can may be conveniently charged and operated to dispense its charge, and whereby 15 the storage space is automatically closed when the can is not in use.

Another object is to provide a closure for a safety can, adapted to yield to relieve internal gas pressure in the storage space, and 20 to automatically close when the pressure is relieved.

Another object is to provide a safety can, the flexible dispensing hose of which is provided with a two-part nozzle, one part adapted for use in pouring into a relatively large receiving orifice, and the other into a smaller orifice. 25

Of the accompanying drawings forming a part of this specification,—

30 Figure 1 is a perspective view of a can embodying the invention.

Figure 2 is a section on the plane indicated by the line 2—2 of Figure 1, omitting the hose.

35 Figure 3 is a fragmentary sectional view similar to a portion of Figure 2, showing the valve opened.

Figure 4 is a fragmentary sectional view, showing the variable nozzle shown by Figure 1.

40 The same reference characters indicate the same parts in all of the figures.

A can embodying the invention is made of sheet metal, the parts being joined together 45 in the usual manner. To simplify the drawing, I have conventionally shown in Figures 2 and 3, parts which are in section, without indicating the joints and seams where the parts are united.

50 The body 12 of the can has the usual bottom 13, and is extended above the storage space 14. The upper end of the body is provided with a head 15, having a filling opening 16, provided with a closure 17, and a dispensing outlet, 55 which preferably includes a nipple 18, fixed

to the head, and a flexible hose 19, fixed to the nipple. The head 15 is preferably flat and is called the outer head, to distinguish it from the head 18, next described, which I call the inner head. 60

The inner head 18 is funnel-shaped, and is preferably an inverted hollow cone frustum joined at its larger end to the body 12, and extending inwardly and downwardly from the outer head 15. The opening at the smaller 65 inner end of the funnel-shaped head communicates with the storage space 14, and is bounded by an annular valve seat 19 (Figure 3), which defines the passage through which liquid flows to and from the storage space, 70 and is arranged so that when the valve hereinafter described is closed upon it, the storage space is tightly closed.

The valve seat 19 may be provided in any suitable manner. In this instance, it is the 75 upper end of a metal ring 20, preferably of brass, soldered or otherwise secured to the inner head 18, said upper end being preferably ground, so that it constitutes an accurate valve seat.

80 Associated with the valve seat is a valve 21, adapted to bear closely on the seat 19, and close the storage space. The valve is fixed to a stem 22, which is movable in a guide in the outer head. The valve is preferably composed of a disk of compressible material, such as leather, and metal disks or washers 23 and 24, one above and the other below the leather disk. The stem 22 passes through the members of the valve and may be secured thereto by any suitable means, such as cotter pins 25, inserted in the stem above and below the valve. The stem is provided above the outer head 15, with a pull handle including a grip member 26, whereby the stem may be moved to open the valve. A spring 27, interposed between the outer head and the valve normally closes the valve on the seat 19. 90

100 The heads 15 and 18 form a space communicating with the filling inlet and the dispensing outlet, the arrangement being such that when the valve is opened, as shown by Figure 3, the storage space 14 may be charged through the filling inlet 16 and the inner head, and the can may dispense liquid through the inner head and the dispensing outlet, the inner head constituting both a charging and a dispensing funnel. The valve opens outwardly, and is adapted to yield and relieve gas pressure caused by vola- 105

tilization of liquid in the tank. When the pressure is relieved, the valve is automatically closed by the spring.

To facilitate the operation of the can and the opening of the valve, I provide a lifting handle fixed to the outer head 15, and including a grip member 30, located above and substantially parallel with the grip member 26 of the pull handle, the relative arrangement of the two grip members being such that digits of a hand grasping the member 30 may be applied to the grip member 26 to open the valve, either when the can bears on a support, or is supported by the operator's hand.

Although the inner head 18 and the valve 21 constitute a liquid-tight end or head portion of the can, adapted to prevent escape of liquid from the storage space, when the valve 20 is closed, I prefer to embody in the can a supplemental head 31, preferably having the usual form of a frusto-conical can breast. The larger end of the head 31 is joined to the body 12, and its smaller end to the inner head 18, outside the valve seat 19. The supplemental head braces and supports the funnel-shaped inner head 18, and the valve seat against the pressure of the spring 27, and constitutes a conical top of the storage space, preventing the pocketing of gas under the funnel-shaped head 18. All gas accumulating in the storage space 14 is permitted by the supplemental head 31 to escape through the opening surrounded by the valve seat, 35 when the valve is opened by the gas pressure, the gas escaping through the dispensing outlet 18.

The ring 20 on which the valve seat 19 is formed, may be extended downwardly, as shown by Figure 2, so that it form a tube projecting into the storage space and provided with perforations 32, permitting liquid to enter the storage space 14, and to be dispensed therefrom. The tube has a bottom 33 in which is an orifice forming a guide for the lower end portion of the valve stem 22. Gas accumulating in the storage space 14 enters the tube and opens the valve when its pressure is sufficient to overcome the spring.

The can body may be provided with any suitable lower grip member adapted to be grasped by one hand of the operator, to tip the can when the latter is lifted by a hand grasping the grip member 30, and manipulating the grip member 26 of the valve stem handle. The lower grip member, in this instance, is provided by a flange 34 projecting below the bottom 13.

To the free end of the flexible hose 190, is fixed a relatively large nozzle 35, adapted to be inserted in the filling orifice of the storage tank of a motor vehicle. 36 designates a smaller nozzle or reducer adapted to be removably connected with the nozzle 35, and formed to enter the receiving orifice of a

vacuum tank. The nozzle 36 is fixed to an annular plug 37, preferably of cork, adapted to be inserted in the nozzle 35. A flexible tether 38 is connected at one end with the nozzle 35, and at its opposite end with the nozzle 36.

The grip member 30, arranged as shown by Figure 1, constitutes a guard for the valve stem and its grip member 26, preventing liability of the accidental opening of the valve.

The tube provided with the perforations 32, and the stem-guiding bottom or portion 33 constitutes a foraminous partition interposed between the inner head 18 and the storage space of the can, and so arranged that all liquid entering the storage space flows through said perforations from the inner head, and all liquid dispensed from the storage space flows through the perforations to the inner head.

Said foraminous partition is adapted also to prevent the ignition of gas and liquid in the storage space by gas ignited outside the partition, so that should gas be accidentally ignited above the storage space, and outside the partition, back firing to gas in the storage space is prevented by the partition.

I claim:

1. A safety can comprising a body, a bottom, an outer head having a filling inlet and a dispensing outlet, a funnel-shaped inner head joined at its larger end to the body, extending inwardly and downwardly from the outer head, and having a central opening communicating with the storage space of the can, and bounded by an upwardly facing valve seat, a valve formed to bear on the valve seat, a stem fixed to the valve, movable in a guide in the outer head, and provided above the outer head with a pull handle, and a spring interposed between the outer head and the valve, and normally closing the valve on the seat, the outer and inner heads forming a space communicating with the filling inlet, the dispensing outlet and the storage space, the arrangement being such that when the valve is opened, the storage space may be charged through the filling inlet and the inner head, and the can may dispense liquid through the inner head and the dispensing outlet, the valve being adapted to yield and relieve gas pressure within the storage space.

2. A safety can as specified by claim 1, the pull handle including a grip member at its upper portion, the can being provided with a lifting handle fixed to the outer head and including a grip member spaced above the grip member of the pull handle, the arrangement being such that a hand grasping the grip member of the lifting handle may also engage the grip member of the pull handle to open the valve.

3. A safety can as specified by claim 1, comprising also a supplemental internal head joined to the body and to the inner end of

the inner head, and supporting the valve seat against the pressure of the valve spring, said supplemental head constituting the top of the storage space, and preventing the pocketing of gas under the inner head.

4. A safety can as specified by claim 1, comprising also a foraminous tube fixed to the inner head and surrounding and extending downwardly from the opening thereof, 10 the end of the tube being open and formed to constitute the valve seat, the tube being provided with a bottom having a guiding orifice through which the valve stem extends.

5. A safety can having a flexible dispensing spout fixed at one end to the can and provided at its free end with a nozzle adapted to be inserted in a relatively large receiving inlet, and with a reducer composed of a smaller nozzle having an annular plug removably insertible in the larger nozzle, the 20 two nozzles being flexibly connected by a tether.

In testimony whereof I have affixed my signature.

FORREST S. BLANCHARD.
